UNITED STATES PATENT OFFICE.

ROBERT HERMANN THIELEMANN, OF LICHENSTEIN, GERMANY.

FURNITURE.

SPECIFICATION forming part of Letters Patent No. 542,661, dated July 16, 1895.

Application filed July 17, 1894. Serial No. 517,824. (No model.)

To all whom it may concern:

Be it known that I, ROBERT HERMANN THIELEMANN, a subject of the King of Saxony, and a resident of Lichtenstein, in the Kingdom of Saxony, German Empire, have invented certain new and useful Improvements in Furniture, of which the following is a full, clear, and exact description.

The present invention consists of a device in connection with tables, desks, and the like, by means of which the feet and legs of the occupant may be kept warm.

It is well known that many people whose vocation necessitates their sitting at a desk or table for the greater part of the day suffer from cold feet during winter, a fact which besides personal discomfort generates also a number of diseases. The disadvantage is obviated by means of the present invention, which comprises a combined table or desk, stool or chair, and device for warming the feet and legs arranged underneath the said table or desk before the stool or chair in the manner hereinafter more particularly described; and in order to make this specification more easily intelligible reference is had to the accompanying drawings, in which similar letters denote similar parts throughout the several views.

Figure 1 is a side elevation of the device; Fig. 2, a horizontal section on the line *a b*, Fig. 1; Fig. 3, a vertical cross-section through the desk; Fig. 4, a plan of the desk-slab; Fig. 5, a detail side elevation of the mechanism for adjusting the position of the desk-slab; Fig. 6, a plan of Fig. 5 with the retaining springs for the slab in position in the rails thereof; Fig. 7, a similar plan showing the said springs disengaged.

The device consists of the outer structure *D*, advantageously in the form of a desk having an interior lining of zinc *Z* and an intermediate layer of felt *F*. Within the shell *G*, which is open at the front part where the occupant is intended to sit, is a second casing of zinc *Z'*, both shell and casing being covered in by a top plate or covering *C*. The interior casing *Z'* has covering of cane *R*, woven in the usual manner and stretched in a metallic frame *R'*, corresponding in shape and size to the interior configuration of the said casing. The side of this interior casing,

against which the chair *T'* is situated, only extends from the base-plate up to the seat of the chair, so that the two casings *Z* and *Z'* 55 enclose an intermediate space having the plan form of three sides of a square, Fig. 2, the said space being closed in on the chair side by the strips *T* *T*' *T*'' *T*''' *T*'''. Thus the occupant of the chair can sit on the same with his feet 60 and legs extending into and resting on the floor of the interior of the casing *Z'*, direct contact with the zinc walls being prevented by the cane-covering *R*.

Within the space between the bottoms of 65 the exterior and interior casings *Z* *Z'* a ring of steam-distributing nozzles *K*, having a steam-supply pipe *D*, lead upward and through the top covering *C* to a stop-valve *A* and then outward, Fig. 1, in any convenient direction. 70 Thus a steam-jacket is formed around the chamber in which the occupant of the chair has his legs. Upon the top plate *C* and communicating with the interior of the steam-jacket is a safety-valve *S*, while in the base-plate a valve *V* is arranged, having a protecting-cap *E* and operated by means of any suitable lever system *S* *t*, Figs. 1, 2, and 3, by a button or handle arranged on the top of the plate *C*. A thermometer *T* is arranged upon 75 the latter plate by which to control the temperature of the steam-jacket. The valve *V* is for letting off the condensed water from the steam-jacket, and when employed the cap *E* should first be removed. 80

On an extension *T* of the base-plate the chair *T'* is arranged, having folding seat *T*'' adapted to fold onto the back of the chair so as to facilitate getting into position before the desk. The valves and other devices on 85 the plate or covering *C* are covered by the slab of the desk *P* which is advantageously made adjustable and arranged in the following manner: On suitable upwardly-extending arms or brackets *t* *t*' of the plate *C* or upper part of the casing *G*, Figs. 1 and 5, are fixed horizontally-extending arms *t*', Fig. 5, carrying guide rolls *r* *r*', Figs. 6 and 7, in grooves, of which L-shaped rails *s* *s*' are mounted to run, said rails being supported at their forward ends on rolls *s*'' *s*''', mounted on arms *s*'' *s*''', supported on the plate *C*. The writing plate or slab *P* is hinged at its forward ends at *c* *c* to two rails *s* *s*', which latter have their ends 90 95 100

rounded upwardly at s' to form stops, as hereinafter described. At the rear side of the plate—*i. e.*, the side farthest from the writer two graduated sector-bars m are pivoted to the under side of the said plate P at l , said sectors being each adapted to slide in slots of the corresponding rail s , so that the slat can be tilted and supported at any desired angle in the substructure G by means of the set-screws n of the said rails s , which clamp the said sector-bars in any position. The slab P can further be slid backward from the occupant, as shown in dotted lines in Fig. 1, and is arrested in its forward or normal position by means of the following device: To the arms t' , Figs. 5, 6, and 7, are fixed flat springs f , carrying at their free ends studs z , adapted when the slab is in its normal position, to engage in orifices or slots e of the upwardly-extending web of the rails s . Suitably guided on the web of the said rails is a wedge-shaped sliding block g , attached by a connecting line or rod to one end of a pivoted lever k pivoted to the under side of the slab P . The inclined surface of this slide-block g is adapted when drawn forward by moving the lever k into the position shown in Fig. 7 to contact with the pin or stud z of the spring f , and push the same back out of the slot e of the rail so that the slab P can then be pushed backward away from the occupant into the position shown in dotted lines in Fig. 1. On releasing the lever k the block g will return to its original position under the pull of its spring i . Thus, in order to push the slab back to facilitate getting into position before the desk or table, it is only necessary to pull back the levers k and push the slab out, its outward movement being determined by the rounded-up ends of the rails s contacting with the front guide-rolls r . In order to get into position before the desk it is advantageous to fold up the seat of the chair and push back the slab P , then to put down the seat, sit down on the same, and put the legs into the interior chamber Z' , at the bottom of which a stiffening-ring I , having feet resting on the base-plate is provided to prevent treading through the zinc lining. The

slab may then be drawn forward and the 5° temperature within the steam-jacket regulated as desired. If deemed necessary, buttons H may be arranged on the plate C for the reception of a covering for the knees.

Instead of steam heating any other suitable 55 heating may be employed, although the former is advantageous.

By means of this apparatus the feet and legs of persons sitting at the desk will be held continually warm. 60

I claim as my invention—

1. A desk or table, having an outer shell or substructure, an inner chamber within said exterior shell to receive the occupant's legs and feet, a covering plate common to both 65 shell and interior casing an adjustable slab mounted on and above said cover means to adjust the same and means for heating the space inclosed between the said shell and interior casing substantially as described. 70

2. A desk or table having an exterior shell and an interior chamber, a cover common to both an adjustable slab mounted on said cover, a steam distributer between the shell bottom and inner casing bottom, steam supply pipe to said distributer, means for regulating the steam supply and a condensed water cock arranged in the bottom of the exterior shell substantially as described. 75

3. A desk or table, having an outer shell or 80 substructure, an inner chamber within said exterior shell, a covering plate common to both shell and interior casing means for heating the space between said shell and interior casing, an adjustable slab, sliding rails 85 hinged to said slab, fixed guide rolls to said rails and means for arresting said rails in their forward or normal position, sector bars hinged to said slab, and guided in slots in the rail ends and means for clamping said sectors 90 in any position substantially as described.

In witness whereof I have hereunto set my hand in the presence of two subscribing witnesses.

ROBERT HERMANN THIELEMANN.
